US00D619558S

(12) **United States Design Patent**
Seil et al.

(10) **Patent No.:** **US D619,558 S**
(45) **Date of Patent:** **** Jul. 13, 2010**

(54) **TRANSMITTER**

D496,639 S 9/2004 Deubler, Jr.

(75) Inventors: **Oliver Duncan Seil**, Pasadena, CA (US);
David Kleeman, Marina Del Rey, CA
(US)

(Continued)

(73) Assignee: **Belkin International, Inc.**, Playa Vista,
CA (US)

OTHER PUBLICATIONS

(**) Term: **14 Years**

(21) Appl. No.: **29/299,757**

(22) Filed: **Jan. 3, 2008**

(51) **LOC (9) Cl.** **14-03**

(52) **U.S. Cl.** **D14/155**

DESCRIPTION

FIG. 1 is a front view of a first embodiment of the transmitter;
FIG. 2 is a back view of the first embodiment of the transmitter;

FIG. 3 is a right view of the first embodiment of the transmitter;

FIG. 4 is a left view of the first embodiment of the transmitter;
FIG. 5 is a top view of the first embodiment of the transmitter;
FIG. 6 is a bottom view of the first embodiment of the transmitter; and,

FIG. 7 is a front, top, right isometric view of the first embodiment of the transmitter.

The broken lines in the drawings are for illustrative purposes only and form no part of the claimed design.
